INVENTOR

Evona S. Roe
By Conrad A. Dutcher
her ATTY.

UNITED STATES PATENT OFFICE.

EVONA S. ROE, OF PATCHOGUE, NEW YORK.

HOSE ATTACHMENT.

Application filed September 27, 1921. Serial No. 503,503.

My invention relates to improvements in washing devices, and the same has for its object more particularly to provide a simple, convenient and efficient device for supplying water, as desired, to a sponge, cloth or the like.

Further, said invention has for its object to provide a device which will readily fit into the hand of the user whereby to supply fluid to a sponge, or other article also held in the same hand by the user.

Further, said invention has for its object to provide a device which may be conveniently connected to a suitable source of fluid supply, and having means whereby the fluid may be supplied, at the will of the user, to a sponge or other article held in position against said device.

Further, said invention has for its object to provide a device of the character specified having a valve which is maintained normally closed and the operating means normally in projected position by the pressure of the fluid to be controlled.

Other objects will in part be obvious and in part be pointed out hereinafter.

To the attainment of the aforesaid objects and ends my invention consists in the novel details, construction, connection and arrangement of parts hereinafter more fully described and then pointed out in the claims.

In the accompanying drawings forming part of this specification—

Figure 1 is a face view showing one form of device constructed according to and embodying my said invention.

Fig. 2 is a side or edge view thereof, partly in section, and illustrating the method of using the same, and

Fig. 3 is a central vertical section of the device.

In said drawing, the device is represented as consisting essentially of a shallow, circular receptacle 10, having a continuous wall 11. From the opposite side of said wall 11 extend radial projections 12, 13 which are so shaped and positioned as to serve as supports to rest upon the thumb and little finger, respectively, when the device is held in the hollow of the hand of the user.

At the lower edge of the receptacle 10 is provided an inlet nozzle 14 which is preferably formed integrally with the base of the receptacle, and extends upwardly to about the center thereof, and terminates in an out-

let 15 arranged centrally within the receptacle 10 upon the base thereof.

The inlet nozzle 14 is provided at its outer end with a shoulder 16 upon which is disposed an interiorly threaded coupling-sleeve 17 adapted to engage with the threaded member 18 secured to the hose, flexible pipe 18' extending from a source of water supply.

19 denotes a spherical valve which is adapted to seat, under the pressure of the water, against an annular washer 20 disposed within the coupling sleeve 17, and resting against the shoulder 16. 21 denotes a valve stem which extends from the valve 19 through the inlet nozzle 14 and said receptacle 10 upwardly, and projects through the wall 11 at the top of said receptacle where the same is secured to a curved finger portion 22 which conforms substantially in outline with the circular contour of the receptacle 10, and has its ends slightly turned upwardly at 23^a, 23^b, to be engaged by the ring and the index fingers, respectively, while the intermediate portion is adapted to be engaged by the middle finger.

The finger portion 22 is provided upon its under side adjacent to one end with a depending pin 24 which extends through a suitable opening provided in the wall 11 of the receptacle 10 in order to guide said finger portion in its movements.

The outlet 15 is provided with a cover 25 which is pivotally secured at its lower end by a screw 26, and is provided at its upper end with a finger portion 27 whereby the said cover 25 may be moved to one side in order to uncover completely the outlet 15 and permit the water to issue in the form of a single column. The cover 25 is provided with a plurality of apertures whereby to break the column of water into a number of small jets which will effectually supply water to all parts of the sponge 28 or other article held in place over the open front of the receptacle. 29 denotes a stop which serves to maintain the cover 25 duly positioned over the outlet 15, when the water is to be supplied to the sponge or other article in finely divided jets.

The operation of the device will be largely obvious. It is only to be noted that the sponge or other article used in the operation of washing is not to be secured to the receptacle 10, but merely held in position over and against the open front of said recep-

tacle by the fingers of the user as illustrated at Fig. 2. When water is to be supplied to the sponge, it merely becomes necessary to depress the finger portion 22, without releasing the hold on the sponge, and thereby unseat the valve 19 whereupon water will be admitted to the receptacle and issue from the outlet 15 thereof in many small jets which will immediately be absorbed by or 10 pass through the sponge 26.

It is to be noted that as the valve 19 is maintained normally seated under the pressure of the water to be controlled, the finger portion 22 will be maintained normally projected and in position to unseat the valve 19 by a slight pressure as and when water is required. By this arrangement and construction all undue waste of water is avoided.

Having thus described my said invention what I claim and desire to secure by Letters Patent is:

1. A device of the character specified comprising a shallow inelastic receptacle shaped to fit the hollow of the hand and to engage a sponge or analogous article, and rigid supporting members projecting radially outwardly from the periphery of said receptacle at opposite sides thereof and adapted to be engaged by the outer fingers of the hand for supporting said device; said supporting members permitting of the device being held in the hand with the fingers available for holding said article in engagement with said receptacle, substantially as specified.

2. A device of the character specified comprising a shallow inelastic receptacle constructed to fit the hollow of the hand and to engage a sponge or analogous article, separate finger engaging supporting members projecting outwardly from the periphery of said receptacle to permit of the same being held in the hand with the fingers available for holding said article in engagement with the front of said receptacle, and means for supplying fluid to said receptacle, substantially as specified.

3. A device of the character specified comprising a shallow, open inelastic receptacle constructed to fit the hollow of the hand and to engage a sponge or analogous article, and an inlet nozzle at the base of said receptacle communicating with the interior thereof and extending diametrically beyond the periphery of the same; said receptacle and said nozzle being arranged to permit of the device being held in the hand with the fingers available for retaining said article in engagement with the open side of said receptacle, and separate finger engaging supporting members projecting outwardly from said receptacle at opposite sides of said nozzle, substantially as specified.

4. A device of the character specified com-

prising a shallow receptacle shaped to fit the hollow of the hand and to engage with a sponge or analogous article, a nozzle thereon having an inlet, and an outlet arranged centrally within said receptacle, a valve for said nozzle, separate finger engaging members extending outwardly from said receptacle at opposite sides of said nozzle, and means arranged exteriorly of the receptacle and intermediate said finger engaging members for actuating said valve; said finger engaging members and said actuating means being arranged to permit of the retention of said article in position by means of the fingers, substantially as specified.

5. A device of the character specified, comprising a shallow, open receptacle adapted to engage with a sponge or analogous article, supporting members extending outwardly from the opposite sides thereof, an inlet, an outlet arranged within said receptacle, a perforated head therefor, a valve for said inlet, a stem on said valve extending through said receptacle, a finger portion secured to said stem arranged exteriorly to said receptacle and conforming thereto, and means for guiding said finger portion, substantially as specified.

6. A device of the character specified, comprising a shallow, open receptacle adapted to engage with a sponge or analogous article, supporting members extending outwardly from the opposite sides thereof, an inlet, an outlet arranged within said receptacle, a perforated cover therefor movably supported with respect to said outlet, a valve for said inlet, a stem on said valve extending through said receptacle, a finger portion secured to said stem arranged exteriorly to said receptacle and conforming thereto, and means for guiding said finger portion, substantially as specified.

7. A device of the character specified, comprising a shallow, open receptacle adapted to engage with a sponge or analogous article, finger supports extending from the opposite sides thereof, an inlet, means for attaching said inlet to a source of fluid supply, an outlet arranged centrally in the base of said receptacle, a perforated cover plate for said outlet, a valve seat in said inlet, a valve adapted to seat thereon under the pressure of the fluid controlled thereby, a stem extending from said valve through said inlet and said receptacle, and projecting through the side thereof, a finger portion arranged exteriorly of said receptacle intermediate said finger supports and maintained in normally projected position by said valve, and a pin secured to said finger portion and extending into said casing for guiding said finger portion in its movements, substantially as specified.

8. A device of the character specified, comprising a shallow, open receptacle adapted to

engage with a sponge or analogous article, finger supports extending from the opposite sides thereof, an inlet, means for attaching said inlet to a source of fluid supply, an outlet arranged centrally in the base of said receptacle, a perforated cover plate, means for pivotally securing said cover plate to said outlet, whereby to permit of said cover-plate being moved into and out of operative position with respect to said outlet, a valve seat in said inlet, a valve adapted to seat thereon under the pressure of the fluid controlled thereby, a stem extending from said valve through said inlet and said receptacle and projecting through the side thereof, a finger portion arranged exteriorly of said receptacle intermediate said finger supports and maintained in normally projected position by said valve, and a pin secured to said finger portion and extending into said casing for guiding said finger portion in its movements, substantially as specified.

9. A device of the character specified comprising a shallow receptacle constructed to fit the hollow of the hand and to engage a sponge or analogous article, an inlet nozzle at the base of said receptacle communicating with the interior thereof and extending diametrically beyond the periphery of the same, finger supports projecting from said receptacle at opposite sides of said nozzle, a valve for controlling said nozzle, and a finger portion arranged exteriorly of said receptacle intermediate said finger supports and above said nozzle for controlling said valve; said finger supports and said finger portion being arranged to permit of the retention of said article in position by means of the fingers, substantially as specified.

Signed at the city of New York, in the county and State of New York, this 21st day of September, one thousand nine hundred and twenty-one.

EVONA S. ROE.
